UNITED STATES PATENT OFFICE.

GEORGE W. WILLIAMS, SR., OF EAU CLAIRE, WISCONSIN, ASSIGNOR OF ONE-HALF OF HIS RIGHT TO HENRY COUSINS, OF SAME PLACE.

MILKING-STOOL.

SPECIFICATION forming part of Letters Patent No. 230,910, dated August 10, 1880.

Application filed April 19, 1880. (Model.)

To all whom it may concern:

Be it known that I, GEORGE W. WILLIAMS, Sr., of the city and county of Eau Claire, State of Wisconsin, have invented an Improvement 5 in a Milking-Stool, of which the following is a specification.

The object of my invention is to combine with a milking stool or seat a pail-holder consisting of a circular guard or railing and a 10 shelf or platform so arranged as to adjust itself to any uneven surface on which the pail is held at a proper distance from the cow when milking.

The nature of my invention will be shown 15 by reference to the accompanying drawing.

A is the seat or stool; B, wire or iron strap-circle formed in connection with front end of stool or seat, fastened to seat by bolts made on the ends of wire or iron strap K K and staples 20 N, or to the sides of the stool by the same means; H H, holes in top of seat, leaving a strip or handle to carry stool; L L, legs; C, table or

shelf resting on the round G of the front legs when being carried; F, foot of table or shelf; D, slit in the back end of table C, to fasten the 25 same to back leg by bolt E, forming a hinge by which table C may be raised or lowered, allowing foot F to rest on the ground, let the surface be even or uneven; M, rounds to hold the legs firm.

What I claim as my invention, and desire 30 to secure by Letters Patent, is—

The combination of table or shelf C with seat A, supported by round G and attached to back leg by means of slit D and bolt E, 35 forming a hinge by which to raise or lower the same, together with circle B, attached to front end of seat A, so as to hold the pail on table C, substantially as described, and for the purpose specified.

GEORGE W. WILLIAMS, SR.
